DESIGN FOR A PORTABLE FLASH LIGHT

Adolph C. Recker, Watertown, Conn., assignor to The Chase Companies, Incorporated, Waterbury, Conn., a corporation

Application October 11, 1934, Serial No. 53,579

Term of patent 14 years

To all whom it may concern:

Be it known that I, Adolph C. Recker, a citizen of the United States, residing at Watertown, in the county of Litchfield and State of Connecticut,
have invented a new, original, and ornamental Design for a Portable Flashlight, of which the following is a specification, reference being had to the accompanying drawing, forming part thereof.

Fig. 1 is a face view of a portable flashlight
showing my new design;

Fig. 2 is a side view thereof; and
Fig. 3 is an end view thereof.

I claim:

The ornamental design for a portable flashlight as shown.

ADOLPH C. RECKER.
